UNITED STATES PATENT OFFICE.

JOHN KRESGE, OF LOOKOUT, CALIFORNIA.

FOLDING IRONING-BOARD.

No. 893,848.

Specification of Letters Patent.

Patented July 21, 1908.

Application filed June 10, 1907. Serial No. 378,153.

To all whom it may concern:

Be it known that I, JOHN KRESGE, a citizen of the United States, residing at Lookout, in the county of Modoc and State of California, have invented certain new and useful Improvements in Folding Ironing-Boards; and I do declare the following to be a full, clear, and exact description of the same, such as will enable others skilled in the art to 10 which it appertains to make and use the same, reference being had to the accompanying drawings, and to the characters of reference marked thereon, which form a part of this application.

15 This invention relates to improvements in ironing boards and particularly to a folding board and one which may be easily folded and unfolded and one which will be simple and effective and yet easily handled by man 20 or woman. This object I accomplish by means of a folding under-support of simple construction, a means for locking the same in its operative position and by such other and further construction as will appear by 25 a perusal of the following specification and claims.

In the drawings similar characters of reference indicate corresponding parts in the several views.

30 Figure 1 is a side elevation of the complete device as it appears when in operative position. Fig. 2 is a similar view as the device appears in folded position. Fig. 3 is a bottom plan view of the device in its folded position. Fig. 4 is a fragmentary view of the lower end of a brace member.

Referring more particularly to the characters of reference on the drawings 1 represents the ironing board proper. Disposed on the 40 under side of said board is a folding support construction as follows:—Hinged to said board on the under side thereof near the inner end are supporting members 2 having a cross base member 3 resting normally on the floor 5. Said supporting members 2 extend normally vertical and are provided with an upper cross bar abutting against back stops 4 secured to the under side of the board 1. Pivotally secured to the members 2 are 45 the oblique members 6 having a cross base member 7 resting normally on the floor 5.

Pivotally mounted on a pivot member 6^b connecting and extending between the members 6 is an oblique brace member 8 formed 50 in two sections and jointed at its pivoted point by means of a bifurcated end 9 on the

upper section of the member 8, the upper end of the lower section of the member 8 surrounding said pivot member 6^b intermediate the bifurcations of the said end 9. This construction permits both upper and lower sections of the member 8 to be well braced and at the same time to be capable of oscillating freely with respect to each other. Secured to the upper end of the member 8 is a V- 65 shaped member 10 adapted to engage normally with V-shaped notches 11 formed by blocks 12 secured to the under side of the board 1. At the lower end of the brace member 8 is a notch 13 which normally engages with the top of the member 3.

In practice the oblique members 6 and 8 in combination with the upright members 2 form a solid and substantial support for the board 1 and yet leaves a sufficient space beneath the outer end to permit of skirts and similar clothes being drawn thereover. When the board is not in use the notch 13 may be dissociated from the member 3 by reason of the pivotal connection of the lower section of the member 8 to the cross bar 6^b, thus permitting the member 10 to be disengaged from the notches 11 and incidentally the members 2 and 6 to be collapsed near the bottom of the member 1. When the 85 said members are so folded the pivot member 6^a of the members 6 fits into a notch 15 in a block 14 secured to the under side of the board 1, and a button 16 is turned over said notch, thus locking the said members in 90 such folded position.

Thus it will be seen that I have produced such an ironing board as will permit of the same being easily folded and placed away when not in use and yet one which is strong, 95 simple and durable for the purpose for which it is designed.

While this specification sets forth in detail the present and preferred construction of my device still in practice many small deviations therefrom may be resorted to as fall within the scope of the appended claims.

Having thus described my invention, what I claim as new and useful and desire to secure by Letters Patent is:—

In an ironing board, a board proper, upright supporting members therefor, a cross base member on said upright members, oblique brace members pivotally secured to said upright members, a pivot member connecting and extending between said oblique members, an oblique brace member formed

in two sections, a bifurcated end on one of
said sections surrounding said pivot mem-
ber, an end of the other section surrounding
said pivot member intermediate the bifur-
5 cations of said bifurcated end, the outer ends
of both sections being free, the lower section
being provided with a notched end for en-
gaging said cross base member, and means

on the upper section for engaging said
board, as set forth. 10

In testimony whereof I affix my signature
in presence of two witnesses.

JOHN KRESGE.
